Des. 242,463
Patented Nov. 23, 1976

242,463

LAWN BUILDING OR SIMILAR CONSTRUCTION

James T. Cribben, Mechanicsburg, Pa., assignor to Capitol Products Corporation, Mechanicsburg, Pa.

Filed Aug. 2, 1974, Ser. No. 494,282

Term of patent 14 years
The term of this patent subsequent to Dec. 17, 1988, has been disclaimed

Int. Cl. D25—03

U.S. Cl. D25—24

FIG. 1.

FIG. 2.

FIG. 3.

FIG. 5.

FIG. 4.

FIG. 1 is a perspective view of a lawn building or similar construction embodying my new design;

FIG. 2 is a front view thereof with the doors in a closed position;

FIG. 3 is a back view thereof;

FIG. 4 is a side view thereof; and

FIG. 5 is a top view thereof.

I claim:

The ornamental design for a lawn building or similar construction, substantially as shown.
